DEMOUNTABLE STAIR STRUCTURE

Louis J. Brune, Sr., Ocean Springs, Miss.

Application August 9, 1944, Serial No. 548,722

1 Claim. (Cl. 72—96)

1.

This invention relates to improvements in stair constructions.

The primary object of this invention is the provision of a preferably concrete or plastic demountable stair structure which may be assembled or disassembled by an unskilled person. It is relatively simple (having few parts) and durable and may be economically fabricated.

A further object of this invention is the provision of a stair construction including a plurality of stringer and step units which are interconnected in such an efficient manner as to provide a steady and durable stair structure which does not require a concrete base or foundation.

Other objects and advantages of the invention will be apparent from the following detailed description.

In the accompanying drawings, forming a part of this specification, and wherein similar reference characters designate corresponding parts throughout the several views—

Figure 1 is a side elevation of the stair structure showing the various assembled details thereof.

Figure 2 is a rear view of the assembled stair structure.

Figure 3 is a cross sectional view taken thru a portion of the stair structure substantially on the line 3—3 of Figure 2.

Figure 4 is a fragmentary cross sectional view thru the lower portion of one of the stringers of the stair structure.

Figure 5 is a fragmentary cross sectional view taken thru one of the inner connecting parts of adjacent step units.

Figure 6 is a perspective view of the intermediate step unit.

In the drawings, wherein for the purpose of illustration is shown only a preferred embodiment of the invention, the letter A may generally designate the improved stair structure. It may include stringer or side wall units B and C supporting the lower and upper step units D and F respectively and intermediate step unit E.

It is understood that the invention is not to be restricted to any particular number of step units. However, in usual practice the side wall members will be of the same construction, and all intermediate step units will be of the same structure. The top and bottom step units will differ slightly, as shown.

It is preferred to construct the various units of the stair structure of concrete. The concrete may be reinforced if desired. Plastic material of any kind may also be used.

2.

The side wall step supports or stringers B and C each include a body portion 10 having inner and outer base flanges 11 and 12 along the lower margin thereof. The stringer is stepped as 10 stringers usually are to support the units D, E and F, including the vertical sides or engaging edges 15 and the horizontal tread supporting surfaces 17. The latter surfaces 17 are provided with downwardly convergent tapered sockets 18 intermediate the ends of each of these surfaces 17. Preferably one socket in each horizontal surface 17 will suffice, altho more sockets may be used if desired. The top surface 17a of the stringers B and C terminates short of the rear edge 18 of the body 10 and at this corner there is provided a cut-out socket 20.

The lower step unit D includes a vertical riser 25 and a horizontal tread 26 integral therewith. These portions 25 and 26 are of the desired thickness. The riser 25 is plain, altho if desired it may be provided with base flanges. The tread 26 on the under surface thereof at each side is provided with a depending frusto-pyramidal or tapered lug 30 adapted to seat in the lowermost stringer socket 18, as shown in Figure 1 of the drawings. The tread 26 is furthermore provided along the rear marginal portion thereof with downwardly convergent tapered sockets or perforations 31, shown in Figures 5 and 6 of the drawings, which are preferably extended the entire way thru the thickness of the tread to facilitate drainage, should such be needed.

The intermediate step units E are formed somewhat similar to the step unit D, each including a riser portion 25a and a tread portion 26a. The latter are provided with sockets 31a similar to the sockets 31 above described, and also retaining lugs 30a on the under surfaces for the stringers B and C. The feature distinguishing the intermediate step units from the lower step unit D is the provision of retaining lugs 40 on the lower edge of the riser 25a, which are of frusto-pyramidal construction, the same as the lugs 30 above described, adapted to seat in the sockets 31 or 31a, as the case may be, of the tread of the next lower step unit.

The upper step unit F includes a riser 25b and a tread 26b. The former is provided with the lower marginal frusto-pyramidal lugs 40 adapted 50 for seating in the sockets of the next lower step unit tread, and the tread 26b is provided with the frusto-pyramidal shaped stringer receiving lugs 30b adapted to seat in the sockets on the top edge 17a of the side walls or stringers B and C, 55 as shown in Figure 3. The distinguishing fea-

ture of the top step unit F over the other step units is that the tread 26^b along the rear margin thereof, is provided with a depending retaining skirt or flange, the entire width thereof, adapted to seat in the cut-out notches or sockets 20 at the upper rear corners of the stringers B and C.

It is apparent from the foregoing description that the stringers B and C, with the step units assembled as shown, will provide a sturdy and durable stair structure which obviously can be assembled or disassembled by an inexperienced person. The device includes but a few number of parts compared to demountable stair structures of the prior art and it does not require a stabilizing foundation structure, since all of the parts are firmly interlocked. Plastic or cement may be used in the sockets to additionally anchor the lugs if desired, altho such is not necessary.

Various changes in the shape, size and arrangement of parts may be made to the form of the invention herein shown and described, without departing from the spirit of the invention or the scope of the following claim.

I claim:

A demountable stair structure comprising 25 stringers having stepped tread mounting edges provided with laterally closed convergently tapered sockets therein, individual step units each including integral riser and tread portions, the under surfaces of the tread portions having depending inverted pyramidal-shaped lugs interfitting in the sockets of the stringers, the riser portions at the lower edges thereof having inverted pyramidal-shaped retaining lugs thereon spaced from the stringers, and the tread portions 30 of the step units below the uppermost step unit having along the rear margins thereof conver-

5 gently tapered perforations extending through the tread portions from their upper surfaces to their under surfaces and receiving the depending lugs on the lower edges of the riser portions of adjacent step units, whereby said perforations also provide drains, the stringers at the upper corners thereof being notched and the uppermost step unit having a skirt depending from the rear margin of the tread portion along the length thereof and fitting in said notches.
